US0D1010271S

(12) **United States Design Patent** (10) Patent No.: **US D1,010,271 S**
Hammes et al. (45) Date of Patent: ** Jan. 2, 2024

(54) **KIOSK FOR PROCESSING ELECTRONIC DEVICES**
(71) Applicant: **ecoATM, LLC**, San Diego, CA (US)
(72) Inventors: **Jarrod Hammes**, San Diego, CA (US); **John Silva**, San Diego, CA (US); **Ryan Baxter**, Las Vegas, NV (US); **Dario Miticocchio**, San Diego, CA (US)
(73) Assignee: **ecoATM, LLC**, San Diego, CA (US)
(**) Term: **15 Years**
(21) Appl. No.: **29/724,106**
(22) Filed: **Feb. 12, 2020**
(51) LOC (14) Cl. **99-00**
(52) U.S. Cl. **USPC D99/28**
(58) **Field of Classification Search**

(57) CLAIM

The ornamental design for a kiosk for processing electronic devices, as shown and described.

DESCRIPTION

FIG. 1 is a top, front, right side perspective view of a kiosk for processing electronic devices showing our new design; FIG. 2 is a bottom, front, left side perspective view thereof; FIG. 3 is a front elevation view thereof; FIG. 4 is a back elevation view thereof; FIG. 5 is a left side elevation view thereof; FIG. 6 is a right side elevation view thereof; FIG. 7 is a top plan view thereof; and, FIG. 8 bottom plan view thereof.

The broken lines shown in the drawings represent portions of the kiosk for processing electronic devices that form no part of the claimed design.
